UNITED STATES PATENT OFFICE.

HOWARD M. DUDLEY, OF PHILADELPHIA, PENNSYLVANIA.

DYEING-MACHINE.

1,274,396.

Specification of Letters Patent.

Patented Aug. 6, 1918.

Application filed February 15, 1917. Serial No. 148,712.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to a dyeing machine and refers particularly to a machine adapted for the dyeing of textile fibers compressed within a dyeing chamber, the dyeing being accomplished by the forced passage of the dye liquor through the fiber mass.

Among the objects of my invention is a dyeing machine particularly suitable for the dyeing of warps in the ball, whereby the condition of the fiber may be accurately and readily judged at any stage of the treatment without opening the dyeing chamber and whereby even results may be obtained without disturbing the fiber to be dyed.

Another object of my invention is a dyeing machine in which the dyed goods may be after-treated with water, steam, air, or other materials or substances without handling the dyed goods.

Other objects of my invention will be evident upon a consideration of my specification and claims.

I have found that the even or uneven dyeings results obtained in a machine of this general character depend largely upon the particular shape of the openings through which the dye liquor enters the fiber mass, and that unevenness can be prevented by the use of openings of a particular shape, the conformation of which enables the liquor to spread itself through the fiber mass without the formation of channels of flow.

I have further found that this desirable result can be obtained if the fiber-mass is supported in the dyeing chamber upon a series of transverse grate-bars.

I have further found that the evenness of the dyeings and treatments may be enhanced by inclosing the fiber in a series of containers and passing the treating liquid through these containers and the fiber contained therein.

In the use of many dyestuffs it is necessary after dyeing to treat the dyed goods with water for washing purposes, or with solutions of chemicals such as metallic salts or oxidizing products, for the purpose of after-treatment, or with oxygen or air for

oxidizing or drying purposes. In the following of these after-treatments it is essential that every portion of the dyed goods be thoroughly and uniformly treated and that the operation be performed as readily and quickly as possible. All of these results are obtainable by the use of the device of my invention, in which the goods are placed in the dyeing chamber and then rapidly, easily and completely dyed and after-treated without further handling of the goods and without the formation of channels by the liquids employed. The device therefore insures even and uniform results with a minimum of time, labor and expense.

One form of my device is shown in the accompanying drawings in which similar parts are designated by similar numerals.

Figure 1 is a side view of one form of my invention, partly broken away to disclose a portion in cross-section.

Fig. 2 is a broken cross-section through the line 2—2 of Fig. 1.

Fig. 3 is an enlarged side view of one of the several fiber-carrying trays, taken in the direction of the arrow 3.

Fig. 4 is a side view of one of the plates of the device.

Fig. 5 is a cross-section through the line 5—5 of Fig. 6.

Fig. 6 is a side view of a modified form of one of the plates.

Fig. 7 is a cross-section through the line 7—7 of Fig. 1, with the plates shown in Figs. 90 and 6.

The outer portion of the dyeing machine, as illustrated, comprises the upwardly converging cover 12 removably attached to the member 13 by the screw bolts 14, 14, the member 13 being movably attached to the shell 15 by means of the screw bolts 16, 16, the shell 15 being attached to the shell 17 by the bolts 18, 18, the shell 17 being attached to the downwardly converging shell 19 by the bolts 20, 20, the shell 19 being attached to the centrifugal pump 21 by the bolts 22, 22. The pipe 23 connects the chamber of the pump 21 with the three-way pipe 24, the latter having the pipes 25, 26 and 27 fitted respectively with the valves 28, 29 and 30. The pipe 25 is connected with an air compressor not shown; the pipe 26 opens into the air and the pipe 27 may be connected with a drain or receptacle as desired. The pump 21 is connected with the pipe 31, which in turn is connected with the pipe 32,

the latter being connected with the pipe 33 carrying the valve 34, the pipe 35 carrying the valve 36 and the pipe 37 carrying the valve 38. The pipe 33 is connected with a 5 dye-dissolving tank, not shown, the pipe 35 is connected with a liquor-reserve tank 39, and the pipe 37 is connected with a water supply.

The object of the reserve tank 39 is to allow of the production and use of a larger 10 quantity of dye liquor than is necessary to fill the dyeing device. By this means the strength of the dye-liquor may be governed to meet the requirements of each individual 15 dyeing operation, and the liquid maintained in a condition where the dye will not be precipitated upon the fiber. It also allows a more uniform supply of liquor to the pump 21.

20 The member 13 is of angular shape, one arm of which 40 fits within the interior face of the shell 15 and is slideable therein, its vertical movement being governed by means of the screw-bolts 16, 16 which thread in 25 the projection 41, 41 of the shell 15.

The pipe 42 connects the upper portion of the interior of the shell 15 with the liquor reserve tank 39 and carries the valve 43. The pipe 44, carrying the valve 45 may be 30 connected with a drain, not shown.

A fixed fiber-tray 46 is within the shell and comprises a series of transverse grate-bars 47, 47, allowing the series of openings 49, 49 between the grate-bars. A series of 35 upwardly extending lugs 70, 70 are fixedly attached to the outer periphery of the bottom of the tray 46, and an annular imperforate side member 71 integral with the grate-bars 47, 47 extends upwardly to the top of 40 the lugs 70, 70, said side member 71 being integral with and fixedly attached to the interior faces of the lugs 70, 70.

The lugs 70, 70 are vertically movable within the lug-chambers 72, 72 of the shell 45 15. The interior of the fiber-tray 46 is therefore formed by the grate-bars 47, 47 and the annular side member 71.

The device is provided with a number of 50 removable fiber-trays 73, 74, the construction of which is similar to that of the tray 46, each tray being capable of a position over and upon the tray beneath it. A similar tray 88 is used as a top tray, no fiber being contained therein.

55 In order to facilitate reference to the various chambers, they will hereafter be referred to as the top chamber 51, the liquor-supply chamber 53, and the lower chamber 54.

A sample dyeing machine 55 exactly similar to the one above described except that it 60 is in smaller proportion and carries the threaded closed top 56 instead of the top 12, is connected to the liquor-supply chamber 53 by the pipe 57 carrying the valve 58. The 65 upper portion of the sample machine 55 is

connected with a pipe 59, capable of being revolved into the position shown by the dotted line 60.

A pipe 61 connects the thermometer 62 with the liquor-supply chamber 53, the pipe 61 being extended beyond the thermometer into the pipe 63, capable of being revolved into the position shown by the dotted line 64.

A perforated steam pipe 65 is within the 75 liquor supply chamber 53.

The top chamber 51 contains a series of pointed plates 66, 66, extending across the chamber. A series of similar plates 68, 68, 80 are situated within the lower chamber 54, 80 and a series of similar plates 75, 75 are situated within the chamber of the pump 21.

The operation of the device is as follows:—

The top 12, the member 13 and the fiber-trays 88, 73 and 74 are removed. The fiber-tray 46 is properly packed with the fiber to be treated, and the fiber-trays 73 and 74, which have been previously packed with the fiber, are placed thereon and the tray 88 placed upon the tray 73. The member 13 is then introduced and moved downwardly by means of the screw bolts 16, 16 threaded in the projecting members 41, 41, the annular member 13 pressing upon the lugs of 95 the tray 88. This downward movement of the annular member 13 is continued until the fiber-trays 46, 88, 73 and 74 are pressed firmly upon each other. Goods are similarly placed in the sample device 55. Valves 100 45, 28, 29, 30, 38 and 34 are closed and valves 58, 43 and 36 are opened, and the pipes 59 and 63 situated as shown by the dotted lines 60 and 64. The necessary dyestuff having been dissolved in the dye-dissolving tank, not shown, connected with the pipe 33, the valve 34 is opened and the centrifugal pump 21 is started. The pump 21 forces the dye liquor upwardly between the plates 75, 75 and 68, 68, in the chamber of the pump 21 110 and the bottom chamber 54, the liquor supply chamber 53, the foraminous bottoms of the fiber-trays 46, 74 and 73, and the goods contained therein, and the chamber 88. As the liquor rises it will pass through the overflow pipe 42 into the liquor-reserve tank 39, from which it will pass through the pipe 35 into the pump 21, thus allowing of a continuous circulation of the dye-liquor upwardly through the device. During this 115 operation the dye-liquor is forced upwardly through the sample device 55 and the goods contained therein. The temperature is varied by means of steam introduced through the steam-pipe 65 and the temperature determined by means of the thermometer 62.

From time to time, the valve 58 is closed, the top 56 of the sample device 55 removed and the goods contained therein examined to determine their condition, and the top 56 120 125 130

replaced and the valve 58 opened and the dyeing operation continued until a test of the goods in the sample device shows them to be properly dyed.

5 The next step is the removal of the dye-liquor contained in the device. This is accomplished by closing valves 43, 34 and 36, opening valve 30 and stopping the pump 21. This allows all of the dye-liquor in the de-

10 vice to drain through the pipe 27 into a suitable receptacle for future use if desired.

The next step is that of washing the excess of dye-liquor from the goods and this is accomplished by closing valve 30 and opening valves 38 and 45, and starting pump 21. This allows fresh water to enter through the pipes 37, 32 and 31 into the pump 21 which forces it upwardly through the device and the goods contained therein and through 20 the overflow pipe 44 into a drain.

The next step is that of oxidizing the dyeings, if oxidizable, by means of air or of drying the goods. This is accomplished by placing the pipes 59 and 63 in the position shown by the full lines, placing the top 12 upon the device, affixing it thereto by means of the screw-bolts 14, 14, and attaching the upper open end of the top 12 to a vacuum or suction pump, not shown. The 25 valves 45 and 38 are closed, the valve 29 is opened, and the pump 21 stopped. The vacuum or suction pump attached to the top 12 thus draws air through the pipe 26 upwardly through the device and the goods 30 contained therein. If the amount of air thus obtained is insufficient for the purposes desired, the valve 28 connecting the pipe 25 with an air compressor may be opened and the valve 29 closed and thus sufficient 35 air may be obtained. It is evident that the air passing through the pipes 25 and 26 may be heated before its introduction into the device, if desired.

The particular formation of the forami- 40 nous bottoms of the fiber-trays 46, 73 and 74 and the tray 88 causes the dye liquor to be spread out and evenly distributed through the goods, causing even dyeings, the similarity of the foramiinous bottoms causes a 45 more regular pressure of the dye liquor within the fiber and the plate members 66, 66; 68, 68 and 75, 75 intensify this distribution and regularity of pressure.

It is to be further noted that the goods 50 are dyed, washed and after-treated or dried without handling, and that all of the operations are under exactly the same conditions, and that the condition of the goods being dyed or treated can be determined at any 55 time during the operation without interrupting the operation by examining the goods in the sample device 55.

In the modification shown in Figs. 5, 6 and 7, the plates 68, 68 of Fig. 1 are replaced 60 by plates similar to plate 67, the exterior of

the device in this modification being preferably circular and conical.

I do not limit myself to the particular size, shape, number or arrangement of parts as illustrated and described, as any or all 70 of them may be varied without going beyond the scope of my invention as described and claimed.

What is claimed, is:

1. In a dyeing machine, in combination, 75 a chamber, a series of movable fiber trays adjacent to each other within the chamber, each tray comprising an imperforate side member and a foramiinous bottom, a chamber below the fiber trays, a series of upwardly disposed plates within the second chamber, and means for forcing a liquid upwardly between the plates in the second chamber and the foramiinous bottoms of the series of fiber trays. 80

2. In a dyeing machine, in combination, a chamber, a series of removable fiber trays adjacent to each other within the chamber, each tray comprising an imperforate side member and a foramiinous bottom of a series 90 of transverse grate-bars, means for holding said trays in position, a liquid supply chamber below the fiber trays, a chamber below the supply chamber, a series of upwardly disposed plates within the last-mentioned 95 chamber, means for forcing a liquid through the device, a reserve tank, means for conducting a liquid from the top of the receptacle to the reserve tank, and means for conducting the liquid from the reserve tank 100 to the liquid forcing means.

3. In a dyeing machine, in combination, a chamber, a series of removable fiber trays adjacent to each other within the chamber, each tray comprising an imperforate side 105 member and a foramiinous bottom, means for holding said trays in position, a liquid supply chamber below the trays, a chamber below the supply chamber, a series of upwardly disposed plates within the last-mentioned 110 chamber, a pump chamber, a pump, a reserve tank, means for conducting a liquid from above the trays to the reserve tank, and means for conducting the liquid from the reserve tank to the pump. 115

4. In a dyeing machine, in combination, a chamber, a series of removable fiber trays within the chamber, each tray comprising a side member and a foramiinous bottom, a testing device proportionate to and similar to, and exterior of, the larger device, and means connecting the two devices whereby a liquid may be forced equally through both, and means for forcing a liquid through both devices. 120

5. In a dyeing machine, in combination, a chamber, a series of removable fiber trays adjacent to each other within the chamber, each tray comprising an imperforate side member and a foramiinous bottom of trans- 130

verse grate-bars, means for holding said trays in position, a testing device proportionate to and similar to, and exterior of, the larger device, and means connecting the two devices whereby a liquid may be forced equally through both, and means for forcing a liquid through both devices.

6. In a dyeing machine, in combination, a receptacle, a series of removable fiber trays 10 adjacent to each other within the chamber, each tray comprising an imperforate side member and a foraminous bottom of transverse grate-bars, means for holding said trays in position, means for forcing a liquid from each tray into an adjacent tray 15 through the series of foraminous bottoms, and means for forcing air through the device.

7. In a dyeing machine, in combination, a 20 chamber, a series of removable fiber trays adjacent to each other within the chamber, each tray comprising an imperforate side member and a foraminous bottom, a chamber below the trays, a series of upwardly 25 disposed plates within the second chamber, a third chamber above the trays, a series of upwardly disposed plates within the third chamber, means for forcing a liquid through the trays, and means for forcing air through 30 the three sets of chambers.

8. In a dyeing machine, in combination, a

chamber, a series of fiber trays within the chamber, each tray comprising an imperforate side member and a foraminous bottom, a testing device, proportionate to and 35 similar to, and exterior of, the larger device, means for forcing a liquid equally through the two devices, means for forcing air equally through the two devices, in such a manner that fiber within the two devices 40 will receive equal treatment.

9. In a dyeing machine, in combination, a chamber, a series of removable fiber trays adjacent to each other within the chamber, each tray comprising an imperforate side 45 member and a foraminous bottom of transverse grate-bars, a chamber below the trays, a series of upwardly disposed plates within the second chamber, a third chamber above the trays, a series of upwardly disposed 50 plates within the third chamber, a testing device, proportionate to and similar to, and exterior of, the larger device, means for forcing a liquid through the two devices, means for forcing air through the two 55 devices and means whereby the fiber in one device may be examined during the treatment of the fiber in the other device.

Signed at New York city, in the county of New York and State of New York, this 12th 60 day of February, 1917.

HOWARD M. DUDLEY.
